NOISE REDUCING ARRANGEMENT FOR USE IN CLOTHES DRYERS

Eugene G. Olthuis, East Cleveland, Ohio, assignor to General Electric Company, a corporation of New York

Application June 11, 1958, Serial No. 741,402

5 Claims. (Cl. 34—133)

This invention relates to apparatus of the type which has a function requiring the exhaustion of gaseous fluid therefrom, such as clothes drying machines for instance, and more particularly to an arrangement for decreasing substantially the noise from such apparatus which normally accompanies the fluid as it flows out through the exhaust.

It is a general object of this invention to decrease substantially the noise, in apparatus having a function requiring exhaustion of gaseous fluid, which passes out through the passage provided to exhaust the gaseous fluid.

A further object of the invention is to provide noise reducing means which will perform its function without impairment of the proper exhaust of the gaseous fluid.

Yet another object of the invention is the provision, in apparatus which is contained within a cabinet such as, for instance, clothes dryers, of a system which will eliminate a substantial part of the noise before it escapes from the cabinet so that the noise does not inconvenience the operator when she is in the vicinity of the apparatus.

In carrying out the invention in one form thereof, I provide a suitable cabinet for enclosing apparatus of the type having a function requiring the exhausting of gaseous fluid therefrom. One typical instance of such apparatus is the domestic clothes dryer. A conduit having an end opening to the exterior of the cabinet so as to provide an exhaust path for gaseous fluid extends within the cabinet for at least a portion of its length. In the case of a clothes dryer, the gaseous fluid is, of course, air, which is frequently exhausted directly to the room in which the dryer is positioned. Suitable means, such as the ordinary blower and motor found in domestic clothes dryers, are provided to cause the gaseous fluid to flow through the conduit. My invention is particularly directed toward means for muffling a substantial part of the noise which would otherwise emerge from the conduit with the fluid. This muffling arrangement contemplates forming at least part of the conduit wall within the cabinet of a sound transmitting membrane of plastic material, positioned in substantially leakproof relation to the remainder of the conduit so that the sound is transmitted through the membrane but the gaseous fluid is kept within the conduit. To absorb the sound thus being transmitted through the membrane into the cabinet, a mass of sound absorbing material is disposed within the cabinet to assist the natural sound-absorbing action of the various components in the cabinet.

The subject matter which I regard as my invention is particularly pointed out and distinctly claimed in the concluding portion of this specification. My invention, however, both as to organization and method of operation, together with further objects and advantages thereof, may best be understood by reference to the following description taken in conjunction with the accompanying drawings.

In the drawings,

Fig. 1 is a side elevational view of a clothes dryer typical of the apparatus in which my invention may be

2

provided, the view being partially broken away and partially sectionalized to illustrate details of the dryer;

Fig. 2 is a plan sectional view of the dryer with the basket removed and with certain surfaces broken away and partially sectionalized to illustrate my improved noise reducing arrangement;

Fig. 3 is an enlarged fragmentary view in perspective of the exhaust conduit forming part of my invention.

Referring now to the drawings, I have shown therein

- 10 a domestic clothes dryer 1 which includes a rotatable open ended tumbling basket 2 mounted within a suitable cabinet 3 which encloses it on all sides. The basket is mounted for rotation about a horizontal axis and comprises a cylindrical drum-like member having an outer cylindrical wall 4 and front and rear walls 5 and 6. The outer cylindrical wall 4 of the basket is imperforate over its entire length and on its interior surface is preferably provided with a plurality of clothes tumbling ribs such as illustrated at 7.
- 15 20 Clothes basket 2 is rotatably supported within the outer cabinet 3 by means of a plurality of roller wheels 8, 9, 10 and 11 (see Fig. 2). Wheels 8 and 9 are mounted on an idler shaft 12 and wheels 10 and 11 are mounted on a drive shaft 13. Shaft 12 has no driving connection to it, but shaft 13 is driven from the drive motor 14 of the dryer through a suitable belt and pulley drive 15. As shown, both the idler shaft 12 and the drive shaft 13 are supported adjacent the front and the rear of cabinet 3 by means of suitable bearings mounted in front and rear support plates 16 and 17. Being freely supported on the roller wheels, basket 2 will turn thereon whenever drive shaft 13 is turned by motor 14, the frictional engagement between the side wall of the basket and rollers 10 and 11 causing the basket to turn as the shaft turns. The ratio 30 of the driving and driven pulleys in the drive 15 is suitably chosen so that the basket is rotated at an appropriate speed to provide a tumbling action for articles of clothing placed therein.
- 35 40 In order that a stream of drying air may be introduced and passed through the clothes basket, the basket is apertured at both front and rear ends. Specifically, a central aperture 18 is provided in wall 5 and a similar aperture 19 is provided in wall 6. Rear opening 19 is substantially covered or closed by means of a stationary bulkhead member 20 which is mounted within the dryer cabinet by means of a pair of cross braces 21 and 22. As shown, a suitable clearance is provided between the edge of aperture 19 and the outer flange 23 of bulkhead 20 so that there is no contact between the basket and the bulkheads during rotation of the basket. The front opening of the basket 18 is likewise substantially closed by means of a stationary bulkhead generally indicated at 24. Bulkhead 24 is made up of a number of adjacent numbers including the inner surface 25 of the access door 26 mounted on cabinet 3, a stationary seat 27 for the door, the inner surface 29 of an exhaust duct 30 leading from the basket, and an annular flange 31 mounted on seat 27 and the wall. All of these members cooperate to define a generally circular bulkhead covering opening 18, with flange 31 at its outer edge surrounding the opening. As with the rear bulkhead, a suitable clearance is provided so that there is no rubbing between the edge of opening 18 and the edge of bulkhead 24 during rotation of the clothes basket.

34 in the rear bulkhead 20, passes through the basket, and then out through a screened opening 35 formed in wall 25 of the door section 33. This air movement is effected in the usual manner by suitable air moving means such as blower 36 driven directly by motor 14. The air then flows through an opening 37 in door 26 which is aligned with an opening 38 in door seat 27 leading to duct 30 when the door is closed. It can be seen that wall 25 of door section 33 is, in effect, a shield to prevent the clothes from plugging opening 38 which may, as shown in Fig. 2, be provided with a grille 39 to prevent clothes from falling into duct 39 during loading and unloading of the dryer. The blower then exhausts the air from the machine to an outlet conduit or duct 40, which will be more fully described below, and which extends from the blower to a relatively large opening 41 provided in the rear of cabinet 3 in communication with the opening at the end of the duct 40. A suitable lint trap 42 may be positioned in any convenient location, such as in duct 30 as shown, to perform the usual function of removing lint picked up by the air in the clothes basket.

The air drawn through the aforementioned duct system by blower 36 is pulled into the basket 2 through opening 34 from an intake duct 43 which is mounted on the rear bulkhead 20 and which is open at its lower end 44 within the cabinet 3. Thus, when blower 36 operates, air is drawn into the cabinet through any suitable openings provided therein for that purpose (not shown), flows to the inlet 44 of the duct 43, through the duct 43, over a suitable heater 45, through opening 34 and into basket 2. The air flow then passes out through opening 35, the door section 33, duct 30, the blower itself, and duct 39 to exhaust opening 41. To prevent any leakage into the basket during this operation suitable air seals 46 and 47 are provided to prevent leakage through openings 18 and 19 respectively. Seals 46 and 47 are preferably formed of felt-like material and are biased against the basket so that in addition to serving as seals they also serve as thrust bearings to maintain the basket in its proper position on rollers 8, 9, 10 and 11. This construction is fully described and claimed in Patent 2,835,048 issued May 20, 1958, to myself and Robert L. Dunkelman and assigned to the General Electric Company, owner of the present invention.

Operation of the dryer to cause the air flow as described may be effected by the setting of manual controls 48 which are normally provided on the front of a backsplasher 49 secured to the cabinet 3 in any suitable position, such as to the back of the top surface of the cabinet.

The operation of motor 14 and of blower 36, the movement of the air within cabinet 3, the operation of the pulley drive 15, and the rotation of the drum all combine to produce noise. It is desirable that this noise level be kept to as low an intensity as possible outside the machine for the comfort of any persons near the machine. In this connection, the arrangement now to be described is provided.

The exhaust duct or conduit 40 is formed as shown of a tubular portion of suitable rigid material such as sheet steel. Within the cabinet 3, duct 40 is provided with at least one opening 50, and preferably several as shown. Within the duct, a thin piece of relatively pliant plastic material 51 is provided. Material 51 is of a type which is thin enough and soft enough to act as a membrane providing for the transmission of sound therethrough but sufficiently non-porous to prevent any appreciable passage of gas or air therethrough. One such material which has been found suitable for the purpose is the plastic known as polyethylene terephthalate which is commercially produced by the Du Pont Company under the trade name "Mylar" in very thin form on the order, for instance, of .00025 inch in thickness. Sheet 51 of this material is arranged within duct 40, 75

preferably in snug contact with the inner surface thereof to prevent leakage of the gas, and thus forms a diaphragm or membrane 52 over each of the openings 50 in duct 40. The important point is that each opening 50 is covered with a diaphragm 52 which permits the passage of a substantial amount of sound without permitting the passage of any of the gas flowing through conduit 40; it will, of course, be understood in this connection that while a solid sheet 51 positioned within duct 40 has been shown, individual diaphragms in connection with the individual openings 50 may be provided, or the sheet may be wrapped around the outside of the conduit 40 with substantial effectiveness insofar as the noise transmission is concerned. In fact, it is conceivable that sheet 51 may itself form part of the duct. However, the arrangement of sheet 51 in a single integral piece within the metal duct 40 represents the presently known most practical method of carrying out the invention.

In order to absorb the sound transmitted through membranes 52 to the interior of cabinet 3, there is provided suitable sound absorbing material 53 preferably arranged as shown to cover a substantial part of the bottom of the dryer and to extend part way up the sides as shown at 54. While any suitable type of material may be provided, the arrangement set forth has proved to be particularly effective when the material is a loosely packed fibrous one such as fibrous glass.

To illustrate the effectiveness of the arrangement of my invention, a standard dryer, of the type having a $\frac{1}{3}$ horse power motor which rotates the basket at 45 r.p.m. and which moves 130 cubic feet of air per minute through the system, was provided with my noise reducing arrangement. The duct 40 was formed of sheet metal $\frac{1}{32}$ inch in thickness and 4 inches in diameter, with a sheet of polyethylene terephthalate film .00025 inch in thickness positioned within it as shown in Fig. 3. Duct 40 was formed with 30 openings in it totalling an area of approximately 40 square inches. The noise level resulting in the vicinity of the machine from this arrangement was 12.03 sones.

This figure compares with a noise level of 16.9 sones for the same dryer when provided with only an ordinary duct 40, i.e., with the openings 50, membranes 52 and sound absorbing material 53 being omitted as in conventional dryers. Thus, the improvement in noise level effected by my invention was substantial.

Thus, it can be seen that the invention provides a simple yet effective means of retaining and absorbing a substantial amount of the noise of the machine 1 within its cabinet 3, without in any way impairing the flow of gas or air through duct 40.

While in accordance with the patent statutes I have described what at present is considered to be the preferred embodiment of this invention, it will be obvious to those skilled in the art that various changes and modifications may be made therein without departing from the invention, and it is therefore aimed in the appended claims to cover all such changes and modifications as fall within the true spirit and scope of my invention.

What I claim as new and desire to secure by Letters Patent of the United States is:

1. In apparatus of the type having a function requiring the exhausting of gaseous fluid therefrom, a cabinet enclosing said apparatus, a conduit extending within said cabinet for at least a portion of its length and having a terminal outlet opening to the exterior of said cabinet, said conduit having an opening formed in its wall within said cabinet, means for causing gaseous fluid to flow through said conduit to be exhausted, and means for muffling a substantial part of the noise which would otherwise emerge with the fluid, said muffling means comprising a sound transmitting membrane of plastic material covering said opening in substantially leak-proof relation therewith, and a mass of sound absorbing material dis-

posed within said cabinet so as to absorb sound as it is transmitted to the interior of the cabinet through said membrane.

2. In a clothes drying machine, a cabinet for enclosing the component parts of the machine, a conduit extending within said cabinet for at least a portion of its length and having a terminal outlet opening to the exterior of said cabinet, said conduit having a plurality of openings formed in its wall within said cabinet, blower means for causing air to flow into said cabinet and out through said conduit, and means for muffling a substantial part of the noise of said clothes drying machine which would otherwise emerge from said conduit with the air, said muffling means comprising sound transmitting membranes of plastic material covering said openings in substantially leak-proof relation therewith, and a mass of sound absorbing material disposed within said cabinet over a substantial portion of the walls thereof thereby

to absorb sound before it leaves said cabinet as it is transmitted into the interior of said cabinet through said membranes.

3. The combination defined in claim 2 wherein said membranes are formed by a sheet of thin pliant plastic material rolled up inside said conduit in snug engagement with the inner surface thereof.

4. The combination defined in claim 2 wherein said membranes are formed of polyethylene terephthalate in thin film form.

5. The combination of claim 2 wherein said mass of sound absorbing material is formed of loosely packed fibrous material.
